UNITED STATES PATENT OFFICE.

CHARLES S. BURTON, OF OAK PARK, ILLINOIS.

PENCIL-SHARPENER.

1,265,743.

Specification of Letters Patent. Patented May 14, 1918.

Application filed December 22, 1913. Serial No. 808,069.

To all whom it may concern:

Be it known that I, CHARLES S. BURTON, a citizen of the United States, residing at Oak Park, in the county of Cook and State 5 of Illinois, have invented new and useful Improvements in Pencil-Sharpener, of which the following is a specification, reference being had to the accompanying drawings, forming a part thereof.

10 The purpose of this invention is to provide an improved mechanism for sharpening pencils and similar work involving the production of a conical or tapered point by cutting. It consists in the elements and 15 features of construction shown and described as indicated in the claims.

In the drawings:—

Figure 1 is a side elevation of a machine embodying this invention.

20 Fig. 2 is a top plan view of the same. Fig. 3 is an end elevation.

Fig. 4 is a section at the line 4—4 on Fig. 5.

Fig. 5 is a section at the line 5—5 on 25 Fig. 2, through the axis of the pencil seat.

Fig. 6 is a section at the line 6—6 on Fig. 5.

Fig. 7 is a side view of one of the cutters.

30 Figs. 8 and 9 are opposite end views of the same.

Figs. 10 and 11 are diagrammatic views to illustrate the law of formation of the cutter, Fig. 10 being an end view of a skeleton of a cutter and Fig. 11 a side view 35 of such skeleton.

The intention of the construction shown in the drawings is to provide revolving cutters having each a plurality of perfectly straight cutting edges, so arranged about 40 the axis of revolution of the cutter as to operate with a draw cut upon the object properly presented in their path, and adapted to have in this respect substantially the same effect and mode of action as is

45 familiarly obtained by cutters having spiral cutting edges. As is obvious, a difficulty in the employment of cutters having spiral cutting edges is the impossibility of sharpening or re-grinding them without employing

50 complicated machinery specially designed for the purpose. The production of a cutter which will operate in the same manner for cutting by means of a perfectly straight edge obviates or greatly reduces 55 this difficulty.

The form of the cutter embodied in this

invention is that which would result from mounting upon the surfaces of a regular polygonal prism flat knives with their cutting edges in the plane of the face on which 60 they are mounted and at an acute angle to the edges of the prism, so that the form described by the revolution about its axis of the prism with the knives so mounted upon it would be conoidal with the surface 65 concave in axial section. Figs. 10 and 11 present respectively an end view, or a view in the direction of the axis, and a side view of what may be called a skeleton cutter produced in the manner above described. 70 The practical cutter is shown in the other figures, being a solid steel body such as would result from filling up the interspaces between the polygonal prism and the knives mounted on it, as above described, so as to 75 leave the knife edges properly protruding and with proper clearance for cutting. This form must be carefully distinguished from a mere conical body, either with cutting edges straight, which could only be the 80 case when these edges are in axial planes, or with the cutting edges oblique and lying in the surface of the cone, which results in such edges being spiral or elliptical, and therefore curved and not straight edges. 85

In the construction shown and preferred, two cutters, A,—A, of the solid form above described are mounted for rotation about their respective axes in a frame, B, which is in turn mounted in a frame, C, for rotation about an axis which has no plane in common with either of the cutter axes. The cutters are positioned in the frame, B, with their axes in such relation to each other that they both describe the same path in the rotation of the frame, B, about its axis in the frame, C; and the planes containing said axes respectively, and intersecting in a line which connects the points of nearest approach of said axes, are at an angle to each other approximately equal to the angle of taper of the cutters, so that the volumes described by the two cutters in their rotation about their respective axes are as nearly 90 tangent to each other as their form, which 95 is concavely curved in axial section, permits. 100

For mounting the frame, B, in the frame, C, as described, the frame, B, is provided with trunnions, B¹ and B², the trunnion, B¹, being hollow for journaling on a bushing 110 sleeve, D, which is mounted in the frame, C, and adapted to serve as the seat or guide

path for the pencil to be sharpened. The trunnion, B^2 , is journaled in a bearing, C^2 , in the frame, C . The frame, C , comprises, or carries as a rigidly mounted portion thereof, an internal gear or rack, E , located in a plane at right angles to the axis of rotation of the frame, B . The cutters, A ,— A , have their shafts at the larger ends extended through their bearings in the frame, B , and provided beyond said bearings with pinions, F ,— F , adapted to mesh with the internal gear or rack, E . The angular relation of the axes of the cutters to the axis of the internal gear or rack, E , it will be seen, is such that for proper meshing of the pinions with the rack teeth, said pinions are twisted or spiral, and also beveled, the teeth of the internal gear or rack being correspondingly formed for smooth coöperation with the pinions. Preferably the frame, C , is constructed so as to have the axis of rotation of the frame, C , horizontal, and the pencil to be sharpened is inserted by the left hand of the operator through the sleeve bushing, D , and advanced for encounter with the cutters, which are encountered at an oblique angle to their axes of rotation and at an oblique angle also to the cutting edges of the cutters. The obliquity of the cutting edges of each cutter to the axis of rotation of the cutter, or, to speak more accurately, their obliquity to lines parallel to the axis and intersecting said edges, respectively, is such as to cause said edges to operate with a draw-cut upon the pencil to be sharpened, the draw being directed toward the point of the pencil. But this obliquity of the cutting edges is not sufficient to cause an adequately long draw cut, and the cut is rendered less abrupt, and more adequately adapted in this respect to the work to be done, by the oblique trend of the pencil with respect to the cutter axes, this obliquity of the axes being added to said obliquity of the cutting edges of the cutters to make the total angle of attack of the cutters upon the pencil such as it should be for a desirable draw cut.

For convenience of assembling, and in order to permit the making of the internal gear or rack, E , of metal more suitable for the purpose than the metal which would be most desirable for the casing, the frame, C , is made to consist of three members, the principal member or standard, C^1 , the outer end cap, C^3 , which comprises the bushing sleeve, D , which forms the pencil seat, and intermediate the two members, C^1 and C^2 , the internal gear or rack, E . These three members are secured together by bolts, H , set through the marginal portion of the cap, and through the internal gear, E , and screwed into the marginal flange, c^1 , on the member, C^1 . In order to protect the gearing from the chips, the cutter frame, B ,

comprises a disk or flange, B^3 , circular about the axis of rotation of said frame, B , and extending off from the hollow trunnion or hub, B^1 , to the inner surface of the casing or standard member, C^1 , so that, revolving with the member, B^1 , within the casing, it constitutes a complete partition between the gears on one side and the cutters on the other side. In view, particularly, of this flange, B^3 , it is convenient to make the frame, B , of two members parting at the plane of the inner surface of the flange, and secured together by a plurality of screws or bolts, J . This construction also facilitates assembling of the instrument.

The space in the member, C^1 , of the standard or casing, C , below the path of the cutters, and at the left of the partition flange, B^3 , serves as a receptacle for chips which may be removed by detaching the removable sheet metal bottom, C^6 , which is shown as formed with a marginal flange, c^6 , which is telescoped within the bottom flange, c^1 , of the standard member, C^1 .

I claim:—

1. A pencil-sharpening machine comprising means for holding the pencil and a cutter mounted for rotation, said cutter having straight cutting edges each positioned in a plane at a distance from the axis of rotation and parallel thereto and each in its respective plane diverging from a line therein parallel to said axis, and means for rotating such cutter about its said axis. 100

2. A pencil-sharpening machine comprising means for holding the pencil and a cutter mounted for rotation having straight cutting edges each positioned in a plane parallel to the axis of rotation, and each in its respective plane diverging from a line therein parallel to the axis; a frame in which such cutter is rotatably mounted, and means by which said frame is mounted for rotation about an axis, the cutter axis and the frame axis being in lines which have no common plane. 110

3. A pencil-sharpening machine comprising a frame having a seat for the pencil; a second frame mounted in the first for rotation about the axis of the pencil seat; a cutter mounted in said second frame for rotation about an axis, said axes of the frame and the cutter, respectively, being in lines which have no common plane; the cutter having straight cutting edges each positioned in a plane parallel to the axis of rotation of the cutter, and each in its respective plane diverging from a line therein which is parallel to said axis, and means for rotating the cutter about its axis in the direction for carrying the end of each cutting edge which is more remote from the axis in advance of the opposite end. 120

4. A pencil-sharpening machine having a

pencil seat, a rotating cutter having straight edges, each positioned in a plane parallel to the axis of rotation, and each in its respective plane diverging from a line therein parallel to the axis, and means for rotating the cutter about its axis in the direction to carry the end of each cutting edge which is more distant from the axis in advance of the other end.

5 5. A pencil-sharpening machine comprising a frame having a pencil seat, a second frame mounted in the first for rotation about the axis of the pencil seat; a cutter having its cutting edges departing farther and farther from the axis of the cutter from end to end, said cutter being mounted in the second frame for rotation about an axis situated in a line non-intersecting with the line containing the axis of the pencil seat; means 15 for rotating the second frame and steering means for simultaneously rotating the cutter about its axis in said frame in the direction for carrying the ends of the cutting edges which are remote from the cutter axis in 20 advance of their opposite ends.

25 6. In a pencil sharpening machine or the like, a milling device comprising a revolv-

ing carrier, a milling cutter mounted in said carrier for independent rotation therein, said milling cutter having its axis of rotation so disposed as to have no plane in common with the axis of said carrier and having its cutting edges departing farther and farther from the axis from end to end, and means for revolving said milling cutter.

30 7. In a pencil sharpening machine or the like, a means for guiding a pencil, a milling device comprising a revolving carrier, a milling cutter mounted in said carrier for independent rotation therein, said milling 35 cutter having its axis of rotation so disposed as to have no plane in common with the axis of said carrier and having its cutting edges departing farther and farther from the axis from end to end, and means for giving said 40 milling cutter a planetary movement about said pencil guide.

In testimony whereof I have hereunto set my hand at Chicago, Illinois, this 19th day of December, 1913.

CHARLES S. BURTON.
